US0D1029547S

(12) United States Design Patent (10) Patent No.: US D1,029,547 S
(45) Date of Patent: * Jun. 4, 2024

(54) STORAGE CABINET

(71) Applicant: Lakeshore Learning Materials, LLC,
Carson, CA (US)

(72) Inventors: Meghan Bruggeman, Lakewood, CA
(US); Queendy Chan, Walnut, CA
(US); Joshua Kaplan, Hermosa Beach,
CA (US)

(73) Assignee: Lakeshore Learning Materials, LLC,
Carson, CA (US)

() Term: 15 Years

(21) Appl. No.: 29/881,711

(22) Filed: Jan. 5, 2023

(51) LOC (14) Cl. 06-04

(52) U.S. Cl.

USPC D6/671; D6/671.1

CLAIM

The ornamental design for a storage cabinet, as shown and described.

DESCRIPTION

FIG. 1 is a front, left perspective photographic view of a storage cabinet showing our new design;

FIG. 2 is a front perspective photographic view thereof;

FIG. 3 is a right side photographic view thereof;

FIG. 4 is a left side photographic view thereof; and,

FIG. 5 is a top perspective photographic view thereof.

The broken lines depicting the remainder of the storage cabinet form no part of the claimed design.

1 Claim, 5 Drawing Sheets
